MOVING CONTACT OF ELECTRIC SWITCHES

Ernst Besag, Streetly, and Thomas D. G. Wintle,
 Birmingham, England, assignors to J. A. Crab-
 tree & Co. Limited, Walsall, England, a British
 company

Application January 31, 1949, Serial No. 73,833
 In Great Britain April 24, 1948

2 Claims. (Cl. 200—166)

1

This invention relates to improvements in and connected with contacts for electric switches, and is particularly concerned with the moving contacts of contactor switches, the principal object being to provide an improved construction which will minimise bouncing of the contact upon its engagement with complementary fixed contacts, thereby reducing arcing and consequent wear.

According to the invention, a spring-pressed moving contact is composed of thin sheet metal which is strengthened by the provision of flanges, ribs or the like thereon. The spring is adapted to maintain engagement of the moving contact with its fixed contacts by overcoming the rebound of the former upon the "making" of the contacts. The provision of a thin contact, preferably made of copper, results in a relatively light mass which is conductive to the avoidance of bouncing, while the strengthening formations impart adequate rigidity to enable the employment of thin metal.

The contact is made of the thinnest metal commensurate with its conductance, that is, the contact is of an adequate cross section to carry the requisite current, the physical strength to compensate for this thinness being imparted by the structural modifications in the form of flanges, ribs or the like. The provisions of these formations enables the employment of a relatively soft metal, such as copper, which constitutes an efficient conductor.

As an example, it may be noted that for the contact strip of an electric motor starting switch adapted to carry 15 amps., the thickness of the metal thereof has hitherto been of the order of .080" and an overall width of .300", this width being required for accommodating the silver contact buttons mounted on the contact strip. According to the present invention, the contact strip for such a switch will have a thickness of only about .018".

The improvements of the present invention enable the contacts to be employed for increased current values without impairing their efficiency. Also the life of the contacts is increased and, hence, the necessity for their renewal and replacement is reduced. The production of the moving contacts from thin sheet metal with strengthening formations thereon, also provides a large surface area in relation to mass, for the purpose of enhancing the dissipation of heat.

In order to enable the invention to be readily understood, reference will now be made to the accompanying drawings illustrating, by way of example, one construction of moving contact car-

2

rier for a three pole contactor switch, in which drawings:

Figure 1 is a perspective view.

Figure 2 is a sectional perspective view with parts disassembled.

Figure 3 is a sectional elevation, the chain lines indicating the fixed contacts and associated parts.

Figure 4 is a section on the line IV—IV of Figure 3.

Figure 5 is a section on the line V—V of Figure 3.

Figure 6 is a perspective view of a modified construction of moving contact.

Figures 2—6 are drawn to a larger scale than Figure 1.

Referring to Figures 1 to 5, the insulating carrier *a* has three vertical recesses *a*¹, in each of which is mounted a moving contact *b* having riveted to each end thereof a silver button *c* for engagement with a fixed contact *d*. Each moving contact *b* is formed from a thin narrow strip of metal having its longitudinal edges bent to form flanges *e* which impart stiffness and strength to the strip, and which provide a contact of channel section. The external flat faces of these flanges *e* afford smooth guiding engagement of the contact with the side walls of the chambers or recesses *a*¹. At a short distance inwards of the buttons *c*, flat stems *f* extend freely through the contact *b*, and constitute mountings for helical compression springs *g*. Each stem *f* may be in the form of a flat arrow having the spring *g* coiled around its reduced part. The head *f*¹ is passed through a slot *i* in the casing while said head is disposed horizontally as shown in the upper part of Figure 2. The stem *f* is then turned to the vertical position shown in the lower half of Figure 2, and its head *f*¹ is passed through a keyhole slot *k* in the contact, after which it is turned again to the horizontal position thus securing the contact *b* resiliently to the carrier *a*. Each contact *b* may be formed with a bulge or bow *b*¹ in the neighbourhood of a keyhole slot *k*.

According to the modified construction shown in Figure 6, the contact strip *b* is formed with downturned flanges *m* at its opposite ends, in addition to the flanges *e* at the sides of said strip. These end flanges *m* may constitute abutments for leaf or blade springs received in the channel formed by said flanges. The flanges *e* and *m* may be formed by bending the strip *b* or by a drawing operation.

Instead of strengthening the strip by the formation of flanges thereon, it may be provided with a dishing extending along a central longi-

tudinal line. Alternatively, other raised formations may be provided for the same purpose.

We claim:

1. In an electric switch, a pair of spaced stationary contacts; an insulating armature carrier mounted between said contacts for reciprocation into and out of contact-closing position with the top and bottom of said carrier spaced inwardly of said contacts; an elongated, light, contact strip of thin sheet metal having strengthening formations thereon; and means for resiliently mounting said contact strip on the front face of the armature carrier with the end portions of said contact strip extending above and below the front face of said carrier and in alignment with said stationary contacts, said means comprising a stem connected to said strip and extending through the front wall of the carrier, and a compression spring surrounding said stem and acting between the inner end thereof and the inner surface of the front wall of said carrier to resiliently maintain said strip in contact with the front face of said carrier.

2. In an electric switch, a pair of spaced stationary contacts; an insulating armature carrier mounted between said contacts for reciprocation into and out of contact-closing position with the top and bottom of said carrier spaced

inwardly of said contacts; a contact strip; and means for resiliently mounting said contact strip on the front face of the armature carrier with the end portions of said contact strip extending above and below the front face of said carrier and in alignment with said stationary contacts, said means comprising a stem connected to said strip and extending through the front wall of the carrier, and a compression spring surrounding said stem and acting between the inner end thereof and the inner surface of the front wall of said carrier to resiliently maintain said strip in contact with the front face of said carrier.
